(57) **CLAIM**

The ornamental design of a display screen or portion thereof with animated graphical user interface, as shown and described.

DESCRIPTION

FIG. 1 is a front view of a display screen or portion thereof with animated graphical user interface, showing a first image of the claimed design; and,
 FIG. 2 is a second image thereof.

The appearance of the animated image sequentially transitions between the images shown in FIGS. 1-2. The process or period in which one image transitions to another forms no part of the claimed design.

The broken line showing of a display screen or portion thereof is for illustrative purpose only, and forms no part of the claimed design.
